FISHING BOX RACK

Tim M. Uyeda, South San Gabriel, Calif., assignor to
Ingersoll-Rand Company, Woodcliff Lake, N.J.

Filed Feb. 25, 1974, Ser. No. 445,805

Term of patent 14 years

Int. Cl. D3—02

U.S. Cl. D87—1

FIG. 1

FIG. 2

FIG. 1 is a side perspective view of a fishing box rack showing my new design, the side opposite, which is not shown, being a mirror image thereof.

FIG. 2 is a side perspective view of a modified form of the design, the side opposite, which is not shown, being a mirror image thereof.

I claim:

The ornamental design for a fishing box rack, as shown and described.
